FISHING SINKER LIFTER

Charles Anaclerio, 243 Hermosa Circle Road, Rancho Cabeza, and Carl R. Anaclerio, 1632 Hillview Terrace, both of Santa Rosa, Calif. 95405

Filed Oct. 20, 1970, Ser. No. 25,565

Term of patent 14 years

Int. Cl. D22—05

U.S. Cl. D22—30

FIG. 1 is a rear perspective view of a fishing sinker lifter showing our new design;

FIG. 2 is a top plan view;

FIG. 3 is a bottom plan view;

FIG. 4 is an elevational view of one side, the opposite side being substantially similar in appearance; and,

FIG. 5 is a front elevational view, the rear elevational view being substantially similar in appearance.

We claim:

The ornamental design for a fishing sinker lifter, as shown and described.
